J. BADEKER.

METALLIC PACKING FOR PISTON RODS.

APPLICATION FILED MAR. 12, 1913.

1,134,091.

Patented Apr. 6, 1915.

UNITED STATES PATENT OFFICE.

JOHN BADEKER, OF OMAHA, NEBRASKA, ASSIGNOR OF FIFTEEN ONE-HUNDREDTHS TO
HENRY W. HARSCH, OF OMAHA, NEBRASKA.

METALLIC PACKING FOR PISTON-RODS.

1,134,091.

Specification of Letters Patent. Patented Apr. 6, 1915.

Application filed March 12, 1913. Serial No. 783,746.

To all whom it may concern:

Be it known that I, JOHN BADEKER, a citizen of the United States, and a resident of Omaha, in the county of Douglas and State 5 of Nebraska, have made certain new and useful Improvements in Metallic Packing for Piston-Rods, of which the following is a specification.

My invention relates to improvements in 10 metallic packing for piston rods and it consists in the combinations, constructions and arrangements herein described and claimed.

An object of my invention is to provide a 15 packing of the type described which will not require the numerous repairs that are necessary in the ordinary packing of this type, but which will continue to work efficiently without the necessity of repair until such time as is necessary for replacing all 20 the packing itself.

A further object of my invention is to provide a packing the parts of which will accommodate themselves to any movement of the piston rod which is in a direction at 25 right angles to its length. This I accomplish by means of springs of a particular type which insure a close fit of the packing on the piston rod without undue friction.

A further object of my invention is to 30 provide a metallic packing comprising a follower which will take up the wear on the packing, thus doing away with the necessity of adjusting the same as the packing is worn.

A further object of my invention is to 35 provide a novel form of metallic packing in which the packing is divided into two or more parts, these parts being held closely to the piston rod by means of springs and 40 by the pressure of the steam when the engine is under steam pressure, but which will retract from the rod slightly when the steam pressure is removed, thereby preventing the undue wear of the parts and also tending 45 to decrease the friction on the rod.

Other objects and advantages will appear 50 in the following specification and the novel features of the device will be particularly pointed out in the appended claims.

My invention is illustrated in the accompanying drawings forming part of this application in which—

Figure 1 is a section through the packing, Fig. 2 is a face view of the casing and fol-

lower, Fig. 3 is a side view of the casing 55 with the packing therein, Fig. 4 is a face view of the body portion of the metallic packing, Fig. 5 is a side view of one of the parts shown in Fig. 4, Fig. 6 is a face view of the body portion of the packing, the movable blocks carried thereby, and the casing, Fig. 7 is a perspective view of one of the blocks, and Fig. 8 is a view of a modified form of the apparatus shown in Fig. 6.

This invention is an improvement on that 65 form shown in my prior Patent #975,813 of November 8, 1910.

Referring now particularly to Fig. 1 I have shown therein a portion of the cylinder head 1 with the piston rod 2 extending 70 through an opening 3 in the head.

The gland 4 which contains the packing is secured to the head by means of bolts 5 or in any suitable manner. The gland is provided with a recessed portion 4^a for the 75 accommodation of the follower and casing. The follower consists preferably of a ring 6 (see Fig. 2) which is provided with a laterally extending flange 6^a on its periphery. This flange has cut-away portions 6^b whose 80 purpose will be explained later. Between the cut-away portions 6^b are inwardly extending lugs 7 which are integral with the flange 6^a.

The packing is made of suitable material 85 such as Babbitt metal and consists preferably of a body portion arranged in two parts. Thus in Fig. 4 I have shown these two parts at 8^a and 8^b. Each portion is provided with recesses such as those shown 90 at 8^a and with integral lugs 8^d extending from the main body portions into the recesses. Each of the sections shown in Fig. 4 is also provided with a lug 8^e immediately surrounded by a circular groove or channel 95 8^f. The lugs 8^e on one of the body portions are arranged to contact with the lugs 8^e on the other body portion.

In Fig. 7 I have shown one of the blocks 9 which are designed to enter the recess 8^e in 100 the body portion proper of the packing. The block 9 is made of soft metal but it is somewhat harder than the metal of the body portions 8^a and 8^b. I have found that where these parts are of the same hardness there 105 is a greater tendency to adhesion thus increasing the probabilities of wear and abrasion. It will be understood, however, that

both of these parts, *i. e.*, the block 9 and the body portions 8^a and 8^b are of metal which is suitable for packing purposes.

The arrangement of the blocks is that shown in Fig. 6. In this figure it will be observed that the blocks 9 engage the lugs 8^a at one end and that they cover the space between the ends of the body portions 8^a and 8^b. It will also be observed that in Fig. 6, I have shown springs 10 which are disposed between the lugs 7 on the flange 6^a. These springs 10 are normally straight pieces of metal. They are bent so as to enter between the interior portions of the flanges 6^a and 15 the exterior portions of the members 8^a and 8^b. The tendency of these springs therefore is to force the packing members 8^a and 8^b toward the piston rod 2.

From the foregoing description of the 20 various parts of the device the operation thereof may be readily understood.

A stout spiral spring 11 is placed in the recess 12 in the cylinder head 1. The follower and casing is slipped over the enlarged part 2^x of the piston rod, the central opening 6^x of the follower being sufficient to permit it to pass the part 2^x readily. The blocks 9 are placed in position in the recesses 8^e of the body portions 8^a and 8^b and the semicircular parts are brought over the piston rod 2 and slipped into the casing formed by the follower 6 and the flange 6^a. It will be noted that the lugs 7 engage the ends of the packing so as to provide spaces between the packing and the flanges 6^a for the springs 10. Furthermore these lugs temporarily retain the blocks 9 before the springs 10 are put in place. These are inserted in the position shown in Fig. 6. The gland 4 is then passed over the portion 2^x and secured by means of the bolts 5 to the cylinder head. If the lugs 7 were not used the first spring 10 to be placed in position would crowd the packing and the flange apart at that side so that a spring could not be easily inserted on the other side of the packing. The lugs 7 prevent this and make it easy to assemble the packing inside of the follower, while the cut-away portions of the flange make the springs accessible for the removal of the packing from the follower. When the packing is to be replaced, the gland is removed and the follower is brought forward until a tool can be inserted in the cut-away portions 55 6^b behind the springs to force them out. New packing parts are then assembled and if the piston rod is hot the two halves are put over the piston rod and a spring wire or split ring 8^x is sprung over the two halves, a groove 8^g being provided for that purpose (see Fig. 5).

The action of the device is as follows:

When the packing is first put in use the movable members 8^a and 8^b are fitted against the rod 2 so as to engage the same uniformly

on all sides. The inward pressure upon the members or segments 8^a or 8^b is then distributed over the whole surface of the rod within the bore of the packing ring. At this time there is very little if any pressure on the lugs 8^e and 8^d. After the packing has been in use for some time the surfaces engaged by the rod are worn away and when so worn the pressure that was at first carried by said surfaces is thrown entirely on to the lugs. Now the area of the lugs is so small that when the pressure is received thereon they are upset and "mushroom" out until the inside surface or bore of the ring is again in contact with the rod, so as to again receive the pressure on these large surfaces and relieve the pressure upon the lugs. This action takes place at such minute intervals that it is practically continuous instead of intermittent.

It will be observed that the springs 10 together with the steam which enters the opening 3 and surrounds the casing both tend to force the movable members 8^a and 8^b toward the piston rod. The lugs 8^e hold the movable members 8^a and 8^b in place. As the interior portions of the members 8^a, 8^b and 9 wear the pressure of the steam which is augmented by the spring 10 causes the lugs 8^e and 8^d to upset or "mushroom," thereby permitting a movement of the packing portions toward the piston rod and thus preventing the escape of the steam. This action will occur until the ends of the semicircular packing members 8^a and 8^b have virtually come into contact. The upsetting of the lugs 8^e causes them to spread into the grooves 8^f while the upsetting of the lugs 8^d is permitted by the space on either side. Now when the steam pressure is removed, as for instance when the engine or locomotive is running down hill, the packing tends to retract slightly from the piston rod, due to the removal of the steam pressure, the springs 10 not being of sufficient strength to hold the 110 packing members closely to the rod. This tends to greatly prolong the life of the packing.

The lugs 7 on the interior of the flanges 6^a not only space the packing members from the flanges, but they also tend to keep the springs 10 in place so that these springs cannot by any possibility overlap, as might be the case if these lugs were not provided.

Any movement of the piston rod at right angles to its length will cause a corresponding movement of the packing and the casing or follower. I have found that where springs such as those shown at 10 are provided they keep the packing normally around 125 the rod. In certain forms of packings of this type, springs are placed on the outside of the packing members, but these springs tend to break. Moreover if spiral springs are used they have not sufficient tension to 130

move the lower part of the packing members to follow the movement of the piston rod at right angles to its length. There is therefore a tendency for the steam to escape, but in my device no such escape of steam is possible, since the packing parts move uniformly with the piston rod.

It will be seen from Fig. 1 that as the surface of the packing members next to the gland are worn the spring 11 will press upon the follower and move the device so as to compensate for any such wearing. It will also be observed that there is a space normally between the follower and the cylinder head so as to provide plenty of room for the packing. The provision of the spring 11 therefore automatically compensates for the wear of the packing and thus reduces the necessity of any adjustment of the packing due to wear until the packing has finally worn out and has to be replaced.

In Fig. 8 I have shown a modified form of the device in which there are three body portions 8^x, 8^y and 8^z of the packing instead of two. The blocks 8^c are carried in the same manner as shown in Fig. 4. It will be observed that the springs 10 in both Figs. 6 and 8 exert pressure near the ends of the packing members 8^a, 8^b and 8^x, 8^y, 8^z. This is precisely the point where the pressure should come to effect proper movement of the packing members due to the wear.

I claim:—

1. A metallic packing for piston rods, comprising a casing having an opening to receive the piston rod, a body portion arranged to enter said casing, said body portion being divided into a plurality of parts, each part being provided with a recess, a block arranged to enter each of said recesses and constituting part of the packing material, means disposed between the walls of the casing and the packing material for pressing the latter toward the piston rod, said last named means comprising a plurality of leaf springs disposed between the wall of the casing and the exterior portions of the packing, and means for preventing the overlapping of adjacent springs and for centering the packing within the casing.

2. A metallic packing for piston rods, comprising a casing having an opening to receive the piston rod, a body portion arranged to enter said casing, said body portion being divided into a plurality of parts, each part being provided with a recess, a block arranged to enter each of said recesses and constituting part of the packing material, means disposed between the walls of the casing and the packing material for pressing the latter toward the piston rod, said last-named means comprising a plurality of leaf springs disposed between the wall of the casing and the exterior portions of the packing, and inwardly projecting lugs

carried by the casing and disposed between the ends of the adjacent springs for preventing the overlapping of the latter, said lugs also serving to space the packing from the walls of the casing.

3. In a metallic packing for piston rods, a follower having a central opening arranged to receive the piston rod, said follower being provided with a laterally extending flange having a plurality of cut away portions, inwardly extending lugs carried by said flanges, said lugs being disposed between said cut away portions, a plurality of metallic packing sections carried by said follower, and a leaf spring disposed between each of said sections and the adjacent flanges for pressing the sections toward the piston rod, a portion of each of said springs being in alignment with a cut away portion in said flange.

4. In a metallic packing for piston rods, a follower having a central opening arranged to receive the piston rod, said follower being provided with a laterally extending flange having a plurality of cut away portions, inwardly extending lugs carried by said flanges, said lugs being disposed between said cut away portions, a plurality of metallic packing sections carried by said follower, and a leaf spring disposed between each of said sections and adjacent flanges for pressing the sections toward the piston rod, a portion of each of said springs being in alignment with a cut away portion in said flange, a gland or casing having a wall arranged to be engaged by the metallic packing, and means for securing said gland to the cylinder head.

5. In a metallic packing for piston rods, a follower having a central opening arranged to receive the piston rod, said follower being provided with a laterally extending flange having a plurality of cut away portions, inwardly extending lugs carried by said flanges, said lugs being disposed between said cut away portions, a plurality of metallic packing sections carried by said follower, a leaf spring disposed between each of said sections and the adjacent flanges for pressing the sections toward the piston rod, a portion of each of said springs being in alignment with a cut away portion in said flange, a gland or casing having a wall arranged to be engaged by the metallic packing, means for securing said gland to the cylinder head, and a spring disposed between a portion of said cylinder head and said follower for holding the packing against the wall of the gland.

6. In a metallic rod packing, a packing ring comprising a plurality of segments disposed around the rod, a follower engaging one side of the packing ring and having flanges extending over the peripheral portion of the ring, and flat springs having

their ends extending between the flanges and packing ring and their intermediate portions extending across between the adjacent peripheral ends of the flanges so as to be accessible from the outside.

7. In a metallic rod packing, a packing ring comprising a plurality of segments disposed around the rod, flat retaining springs having their central portions engaging the segments, a follower engaging one side of the packing ring, peripheral flanges on the follower extending over the end portions only of the retaining springs, and lugs on the inner sides of said flanges to positively limit outward movement of the segments relatively to the follower.

8. In a metallic rod packing, a plurality of main segments fitting upon the rod and

having their adjacent end portions extending approximately radial to the rod, contacting malleable abutments on said adjacent ends of the segments to hold them normally in spaced relation, there being recesses in the segments at one side and adjoining the ends thereof, secondary segments disposed in said recesses so as to lap the adjoining ends of the main segments and engage the rod, said secondary segments fitting against all but one edge of each of the recesses, and malleable abutments for holding said segments normally in spaced relation to the other edges of the recesses.

JOHN BADEKER.
